UNITED STATES PATENT OFFICE.

MELVILLE A. MILLER, OF PITTSFIELD, ILLINOIS, ASSIGNOR TO BRUN-MILL COMPANY,
OF PITTSFIELD, ILLINOIS, A CORPORATION OF ILLINOIS.

COMBINED CIGARETTE AND VANITY CASE.

1,342,178.

Specification of Letters Patent. Patented June 1, 1920.

Application filed September 22, 1919. Serial No. 325,382.

To all whom it may concern:

Be it known that I, MELVILLE A. MILLER, a citizen of the United States, residing at Pittsfield, in the county of Pike and State 5 of Illinois, have invented certain new and useful Improvements in Combined Cigarette and Vanity Cases, of which the following is a specification.

This invention relates to a case designed 10 to contain cigarettes and toilet articles; more particularly it is concerned with certain features of construction, by which the contents of the case are securely held in place.

15 A suggestive embodiment of this invention is illustrated in the accompanying drawings wherein—

Figure 1 is a plane view of the case fully opened;

20 Fig. 2 is a longitudinal section therethrough, taken on line 2—2 of Fig. 1;

Fig. 3 is a transverse section therethrough, taken on line 3—3 of Fig. 2;

25 Fig. 4 is a perspective view of the case partially opened with the mirror outwardly extended for use;

Fig. 5 is a transverse section taken on line 5—5 of Fig. 1, showing the case as closed; and,

30 Fig. 6 is a longitudinal section through a lip stick adapted to be received within the case.

The case proper consists of the usual dished cover sections, designated respectively as 10 and 11, having joints 12 through which is extended a pintle 13 to establish a hinge connection. A tongue 14 formed with joints 15 is also connected to the pintle as shown. A spring 16 tends to 40 open the two cover sections into alinement, as shown in Fig. 2, this same means acting to hold the tongue 14 toward the cover 10. A suitable spring lock is provided for holding the covers together when they are closed, 45 this lock including, among other parts, an ear 17, which is carried on a spring arm 18 suitably secured to the cover 10.

Mounted within the cover 11 as by means 50 of a spring hinge 19 is a frame 20 adapted to carry a mirror 21, which normally lies close up against this cover. I would have it understood, however, that the use of a spring in this hinge is entirely optional and not at all necessary. At the end of the

mirror frame opposite the hinge 19 is a hook 55 22 adapted to engage within a slot or opening 22^a formed in the tongue so that the parts may arrange themselves as shown in Fig. 4. In this position the spring hinge between the two case sections tends to open 60 the covers while the mirror frame acts to nullify this tendency as long as it remains hooked to the tongue. The case covers, however, may freely be retained in partially or fully opened position while the 65 parts continue in this relation. Because of the construction described, the present case is adapted to provide a mirror with stand therefor which may conveniently be set upon a table or other plane surface, the 70 mirror being retained in position at about the angle shown, or being otherwise disposed if it be desired to fully open the case and thereby lift the tongue away from the cover 10.

75 The cover 10 is provided with a plate 23 substantially flush with its edges, from which depend, toward the dished bottom of the cover, walls, one of which designated as 24, defines a compartment within which 80 articles such as cigarettes 25 may be received. Elsewhere other walls 26 provide compartments 27, preferably circular in form, within which may be received powder puffs 28, or, if desired, other small articles. An elongated compartment 29 may also be provided adjacent to the free end of the cover 10 for the reception of a lip stick 30. The tongue 14, which is spring-pressed toward the cover 10, is shown to be 90 provided with a cross arm 31 whose ends are adapted to overlie the powder puffs 28 so as to retain them in place. The end of the tongue, furthermore, extends in overlying relation to the compartment 29 so as 95 to retain therein the lip stick 30. It will be seen, therefore, that the tongue acts to preserve in place all of the articles that are carried in the cover 10.

100 The casing for the lip stick, shown in detail in Fig. 6, may consist of a tube 32 slotted as at 33, and equipped with removable caps 34 at its ends. A plug 35 having a shank 36 extended through the slot 33 is adapted to be moved longitudinally of the 105 tube when proper pressure is applied to the button end of the shank. Lip sticks may be placed within the tube, one at each end,

and either adapted to be projected through the medium of the plug into operative position when its associated cap is removed.

The present case is very simply constructed, and because of the novel arrangement and character of the compartments formed in the cover 10, all of the loose articles therein are adapted to be securely held in place through the sole medium of the tongue 14. This is true whether the covers of the case be closed or opened, and whether the mirror be held with the cover 11, or be opened out into the position shown in Fig. 4.

15 I claim:

1. A case of the kind described, comprising, in combination, a pair of hinged covers having spring means tending normally to open them, a tongue swingingly secured between the covers and having spring means for pressing the tongue toward one of them,

a mirror frame having a hinge connection adjacent the free end of the other cover against which it is adapted to lie, and means carried at the opposite end of the frame 25 adapted to engage with the tongue for holding the frame extended outwardly with the mirror exposed for use, substantially as described.

2. A case of the kind described, comprising, in combination, a pair of hinged covers having spring means tending normally to open them, a frame having a hinge connection with one cover near its free end, and means carried by the frame at its opposite 35 end, adapted to engage with other means swingingly arranged within the other cover, whereby the spring opening means between the two covers is rendered inoperative with the frame extended outwardly between the 40 covers, substantially as described.

MELVILLE A. MILLER.
